UNITED STATES PATENT OFFICE.

JAMES BAKER, OF ST. LOUIS, MISSOURI.

HOT-AIR FURNACE.

SPECIFICATION forming part of Letters Patent No. 410,261, dated September 3, 1889.

Application filed October 24, 1888. Serial No. 289,037. (No model.)

To all whom it may concern:

Be it known that I, JAMES BAKER, a citizen of the United States, residing at St. Louis, in the State of Missouri, have invented new and useful Improvements in Hot-Air Furnaces; and I do hereby declare the following to be a full, clear, and exact description of said invention, reference being had to the accompanying drawings, and to the letters or figures of reference marked thereon, which form a part of this specification.

My invention relates to improvements in oil or gas stoves, and particularly to that class used for heating purposes.

15 The object of my invention is to provide a stove having a large heating-surface and in which all the products of combustion are consumed without smoke or soot.

20 My invention consists in the novel construction of flues and pipes through which the heated air from the lamp or burner is caused to pass first in an upward direction and then down through pipes which discharge the air that has become partially cooled into the room 25 at the lower portion of the heating device.

My invention consists, further, in providing a main flue with the inverted cone around which the heated currents pass, said cone being designed to prevent the back-pressure of 30 the air-currents on the lamp or burner.

Other novel features will be fully described hereinafter, and pointed out in the claims.

Referring to the drawings, Figure 1 is a longitudinal sectional view of my device, showing the lamp in position. Fig. 2 is a vertical sectional view on the line $x-x$ of Fig. 1, looking in the direction of the arrow 1.

A indicates the base of the stove or heater, made of sheet-iron or of other suitable material and of any suitable or desirable shape, said base being perforated with a series of small holes a and provided with a lamp B, or other suitable device for burning oil or gas. In many localities gas is not convenient, and in 45 such cases ordinary coal-oil may be used in any suitable burner; but by preference I use gas, either natural or manufactured, and when gas is used I prefer to use a burner such as is shown, described, and claimed in an application filed by me of even date herewith, Serial No. 289,038. The central upper portion

of the base A is provided with an aperture which communicates with the horizontal drum C by means of the pipe D. The upper portion of said drum C is provided with an opening 55 E, which communicates with the drum F by means of the pipe G.

H is a tapering pipe located in pipe D and extending through the drum C into the pipe G, which communicates with the drums C and 60 F, the lower portion of said pipe H being designed to receive the upper portion of the lamp or burner.

I is a hollow cone secured to the upper end of the pipe H in any suitable manner, and is 65 somewhat smaller than the pipe G, so as to leave a space between the cone I and the pipe G for the passage of the heated air-currents. The object of said cone is to provide against 70 back-pressure on the lamp or burner of the heated air, and thus causing at all times an upward travel of said air-current.

The ends of the drum C communicate with the pipes K near their center, the lower ends of said pipes being arranged to communicate 75 with the interior of the base A, while the upper portions of pipes K are joined to and communicate with the ends of the drum F, as shown in Fig. 1.

L are pipes, the lower ends of which rest 80 upon the upper portion of the base A, while their upper ends communicate with the drum F, the pipes having several small perforations at their lower ends to allow the escape of the hot-air currents into the chamber or compartment. I prefer to arrange these pipes 85 two at each side of the drum F; but any desired number may be used which will produce the best result.

In the central upper portion of the drum F 90 is an opening M, which communicates with the pipe N, said pipe N being closed by the cone-shaped stopper O, said stopper extending down into the drum F some little distance below its center, and the object of which is 95 to deflect the air-current and throw them off toward the end of drum F and into pipes K and L.

A space P is left between the upper end of the pipe H and the opening E of the drum C, 100 so that any excess of hot air may pass into the drum C and from thence to the pipes K.

The lower portion of pipe H is designed to fit snugly within the pipe D by receiving the tapering part of the pipe H.

The space R is left between the pipe H and 5 the pipe D, and at the lower portion of this space the pipe D is perforated with a series of small holes b, which allow any excess of hot air in the drum C to escape into the room, or compartment. The central aperture of the 10 base A is made somewhat larger than the lamp-chimney, and is provided with a sliding damper S, by which the current of air passing around said chimney may be regulated.

The operation of my device is as follows: 15 Air is admitted to the lamp or burner to support combustion in any suitable manner, while the air designed to be heated by the combustion of gas or oil passes into the chamber A through the perforations a, up through the 20 pipe D into the pipe H, where it comes in contact with the hot air produced by the combustion of the oil or gas, and is deflected outward toward the sides of the pipe G by means of the cone I, and passing into the drum F is deflected toward both ends of said drum by 25 means of the cone-shaped stopper O. These hot currents give off their heat through the walls of the drum F by radiation, and as the air becomes cooled it descends into the pipes 30 K and L, and the currents passing through pipes K are discharged into the base A, while the currents descending into the pipes L are discharged through the apertures C.

By this construction and arrangement I 35 am enabled to effect a complete combustion of oil or gas, thus obviating the generation of offensive odors, smoke, or the accumulation of soot.

It will be noticed that no flue or chimney communicating with the exterior air is used, 40 and that all the heat generated is utilized for heating purposes.

What I claim is—

1. A hot-air furnace having a lamp or burner located in the base, a central flue arranged 45 around the lamp or burner, said flue communicating with the base and with horizontal drums, an inverted cone or deflector O, located above the central flue, and the pipes K, communicating with the horizontal drums and 50 with the base, substantially as described.

2. A hot-air furnace having a lamp or burner located in the base, a central flue arranged around the lamp or burner receptacle, a central tapering pipe arranged within the flue 55 and provided with an extension parallel with the central flue, an inverted hollow cone secured to and above the central flue, the pipe K, and the horizontal drums, the central flue and pipes communicating with the drums and 60 base, substantially as described.

3. A hot-air furnace having a base in which the lamp or burner is placed, a central flue arranged around the burner, said flue communicating with the base, horizontal drums 65 with which the flue communicates, pipes communicating with the base and with the drums, and pipes communicating with the upper drum and having openings near the base for the discharge of air, substantially as set forth. 70

In testimony whereof I affix my signature in the presence of two subscribing witnesses.

JAMES BAKER.
